UNITED STATES PATENT OFFICE

1,997,019

HIGH FREQUENCY GENERATOR

Joachim Schloemilch, Berlin-Lichterfelde, Germany, assignor to Telefunken Gesellschaft für Drahtlose Telegraphie m. b. H., Berlin, Germany

Application March 16, 1929, Serial No. 347,718
In Germany April 21, 1928

5 Claims. (Cl. 250—36)

In the production of very short waves, the capacitance and inductance of the leads connecting parts of the circuit manifest themselves in a very disturbing manner. Up to a frequency of about 50,000 kilocycles, generation of waves is still possible by means of normal circuit elements located outside the tubes, but beyond this frequency the capacity and inductance of leads assume such high values that substantial increase 5 in frequency is no longer possible.

10 The present invention provides ways and means to confine all of the circuit elements of a short-wave generator within a glass vessel in order to permit the production of substantially higher frequencies by the adoption of appropriate 15 arrangements; especially, it dispenses with connecting leads.

15 The method of confining circuit elements within a glass vessel or bulb is, per se, well known; but what is novel is the idea of sealing the tuning 20 means inside the exhaust glass vessel so as to make the connecting leads between them and the different parts of the tube (filament, grid, plate) of minimum length.

25 The accompanying drawing shows an exemplification of a short-wave generator in a push-pull circuit scheme, the fundamental principle of which is shown in Fig. 1. Fig. 2 shows a possible disposition of the circuit elements inside the tube.

30 The two electrode systems R and R₁ which are sealed or welded by fusion to glass bridges are directly united with inductances L and L₁. Leads A, B, C, for the supply of filament and plate potential are brought out through the glass stem or foot. Variation of frequency is effected by capacitive means, for example, by means of two sheets D and D₁ welded to the plates and capacitively coupled by means of a sheet cylinder or the like (E). In Figure 2, K K', G G'; P P' denote 35 the filaments, grids and plates, respectively, of the systems R and R₁. The filaments or cathodes K K' are assumed to be of the direct series heated type as illustrated in the key diagram. The supply of plate potential is effected at point B. Regenerative coupling is provided between conductors L and L₁. The tuning capacity is the capacity between the surfaces D and D₁. The small dots shown in Figure 2 indicate the seals or junctions of the connections. The useful or 40 load circuit (antenna circuit) is arranged outside

the discharge vessel and is in inductive coupling relationship with the oscillating electrode system.

Another means, of an inductive nature, for varying the frequency is to approach a short-circuiting ring to the inductance L or L₁. 5

I claim:

1. A generator of high frequency waves comprising an evacuated container, a pair of anodes therein, a pair of cathodes therein, and a pair of grids therein, a single loop of wire connecting the grids together, a single loop of wire connecting the anodes together, said loops being coupled together, means for energizing said electrodes whereby high frequency oscillations are generated, means external of said container 10 cooperating with a pair of elements in said container, but physically unconnected with any of the elements within said tube for varying the frequencies of oscillations generated. 15

2. An arrangement as defined in claim 1 characterized in this, that said pair of elements comprise sheets attached to said anodes. 20

3. An oscillation generator comprising within a single envelope two paths of electron streams, each path comprising a cathode, anode and control electrode, the corresponding electrodes of both said paths being joined together within said envelope by conductors, a connection within said envelope between said cathodes and the conductor joining said control electrodes, an external 25 source of energy in circuit with said cathode and a connection from said source to the conductor joining said anodes, and a connection external of said envelope and physically separated from any of the electrodes, coupled through said envelope 30 to a pair of said corresponding electrodes. 35

4. An oscillation generator of the type defined in claim 3 characterized in this, that said external connection is coupled capacitively between 40 said anodes. 45

5. An oscillation generator comprising two space current devices within a single envelope, conductors within said envelope connecting corresponding electrodes of the two space current devices together, and a connection external of 45 said envelope capacitively connecting together one pair of said corresponding electrodes, said connection being physically separated from the elements within said conductor. 50
